(57)

CLAIM

The ornamental design for a gaming machine and display as shown and described.

DESCRIPTION

FIG. 1 is a perspective view of a gaming machine and display in accordance with the new design.

FIG. 2 is a left side view of the gaming machine and display shown in FIG. 1.

FIG. 3 is a right side view of the gaming machine and display shown in FIG. 1; and,

FIG. 4 is a top view of the gaming machine and display shown in FIG. 1.

The broken lines showing portions of the gaming machine and display form no part of the claim.
